Des. 216,480

Patented Jan. 13, 1970

216,480

WALL PANEL OR THE LIKE

James D. Wilson, 2514 Laurel Lane,
Wilmette, Ill. 60091

Filed Jan. 2, 1969, Ser. No. 15,175

Term of patent 14 years

Int. Cl. D25—01

U.S. Cl. D54—2

FIG. 1.

FIG. 2.

FIG. 3.

FIG. 4.

FIG. 5.

FIG. 6.

FIG. 1 is a perspective view of a wall panel or the like, embodying my new design;

FIG. 2 is a front elevational view thereof;

FIG. 3 is a top plan view thereof;

FIG. 4 is a side elevational view thereof taken from the left side of FIG. 3;

FIG. 5 is a side elevational view thereof taken from the right side of FIG. 3; and

FIG. 6 is a rear elevational view thereof.

I claim:

The ornamental design for a wall panel or the like, substantially as shown.
